[57] CLAIM

The ornamental design for an endoscopic stapler, as shown and described.

DESCRIPTION

FIG. 1 is a perspective view of the endoscopic stapler in accordance with the present invention;

FIG. 2 is a front side elevational view of the endoscopic stapler shown in FIG. 1, the rear side elevational view being a mirror image thereof;

FIG. 3 is a top plan view of the endoscopic stapler shown in FIG. 1;

FIG. 4 is a bottom plan view of the endoscopic stapler shown in FIG. 1;

FIG. 5 is a right end elevational view of the endoscopic stapler shown in FIG. 1; and,

FIG. 6 is a left end elevational view of the endoscopic stapler shown in FIG. 1.

FIG. 3

FIG. 4

FIG. 5

FIG. 6
